UNITED STATES PATENT OFFICE.

VALENTINE MOESLEIN, OF NEW YORK, N. Y.

HAT-SEWING MACHINE.

SPECIFICATION forming part of Letters Patent No. 275,067, dated April 3, 1883.

Application filed August 18, 1882. (No model.)

To all whom it may concern:

Be it known that I, VALENTINE MOESLEIN, of the city, county, and State of New York, have invented certain new and useful Improvements in Sewing-Machines, of which the following is a specification.

My invention is intended more particularly for sewing sweat-bands into hats, and I have for this purpose devised a peculiar construction of the general frame-work and of the needle-operating mechanism, which allows all shapes of hats with brims of greatly varying width to be operated upon with unusual facility. I have also devised means for controlling the position of certain gages or guides, whereby the introduction and removal of the hats is rendered more convenient.

The accompanying three sheets of drawings form a part of this specification, and represent what I consider the best means of carrying out the invention.

Figure 1 is a side elevation of my improved machine. Fig. 2 is a plan thereof. Fig. 3 is a plan of the table of the machine and of the adjacent parts, the presser-foot bar and the needle-bar being shown in section. This and all the following figures are on a larger scale than Figs. 1 and 2. Fig. 4 is a front elevation of the needle-plate of the machine, of the presser-foot and its attachments, of the needle-bar, and of the parts under the plate. This figure shows the presser-foot in the elevated position, and the part which protects the feed and the hook mechanisms turned downward to expose said mechanisms to the view. Fig. 5 is a side elevation, partly in section, corresponding to Fig. 4. Fig. 6 is a similar view, showing the presser-foot in its lowered position. Fig. 7 is a front elevation corresponding to Fig. 4, but with a certain member added, and showing a part of a hat placed in position to be sewed. Fig. 8 is a side elevation of Fig. 7. Fig. 9 is a horizontal section through certain parts on the line *s s*, Fig. 8. Fig. 10 is a plan showing a modification of a detail.

Similar letters of reference indicate corresponding parts in all the figures.

A is the bed-plate of the machine, formed with two standards, *A'* *A*², which form the bearings for the main or driving shaft *B*. The front standard, *A*², also supports the needle-plate *C*, the latter being fixed thereto by means

of a screw, *c*, and one or more dowel-pins. (Not represented.) Motion is imparted to the shaft *B* by any ordinary or suitable means, by hand or through a belt. The drawings represent a fly-wheel, *B'*, formed with two grooves of different diameters for receiving a driving-cord.

D is a goose-neck projecting forward from near the front end of the bed-plate *A*, then upward, and then backward again, its end forming the head *D'*, which carries the presser-foot and the needle-bars.

The needle-bar *E* receives its vertical reciprocating motion through a curved link, *F*, the upper end of which is connected to the needle-bar *E* by means of a screw-stud, *e*, while its lower end is joined to a lever, *G*, by means of a screw-stud, *f*. The lever *G* turns on a center, *g*, and receives its motion from an eccentric on the main shaft *B* through a pitman, *H*, to which its short arm is connected by means of a ball-and-socket joint.

The arrangement of the goose-neck *D* in front of the plate *C*, and the transmission of motion to the needle-bar *E* through a correspondingly shaped and located arm, *F*, and lever *G*, allow the hat *I* (shown in dotted lines in Fig. 1) to be placed in a most convenient position for the operator, without necessitating its being bent out of shape in any of its parts, the crown being entirely free on all sides except at the lower part, where it rests upon the needle-plate, while a sufficient space is provided between the standard *A*² and the goose-neck *D* and link *F* to allow liberal accommodation for the brim of the hat or for the overhanging part of other material to be sewed.

The feed mechanism and the hook *J* for the formation of a chain-stitch may be of any ordinary well-known construction. In the drawings I have shown these parts as of the Willcox & Gibbs style; but it is well understood that I can employ a shuttle for the formation of the stitch.

The spool-support *d* and the thread-tension devices also may be of any approved construction, it being understood that the support *d* be arranged forward of the table *C*, so that the thread passes from the front to the head *D'*, and thence down to the needle, so as not to interfere with the hat-body *I*.

The presser-foot *K* is raised and lowered by

means of an eccentric cam, L, acting in the ordinary manner on a projection on the presser-foot bar.

M is a guide which holds the brim of the hat against the feed and hook protector N, and serves thus to guide the hat along during the operation without the necessity of controlling the direction of its motion by hand. The sweat-leather is fed in under the needle through a slot, k, formed in the presser-foot, as shown, and the sewing on of the sweat-leather is consequently effected with the sweat-leather projecting horizontally out of the crown of the hat, above the guide M, while the latter holds the hat-brim downward in its normal position. When the sewing is completed and the hat is removed from the machine, the sweat-leather has simply to be turned inward into the crown, a fold being thus produced in the sweat-leather along the line of stitching.

In order to facilitate the introduction and removal of the hat without the necessity of bending it out of shape, I mount the guide M in such manner on the presser-foot that it not only rises and descends with the latter, but also that it is turned into a horizontal position when raised. For this purpose the arm m, which carries the guide M, is mounted on a shaft, m', which latter is capable of rocking in the downwardly-projecting part k' of the presser-foot. A spring, m², surrounding the shaft m', tends to turn the latter constantly toward the left, so as to cause the guide M to apply with gentle pressure against the face of the protector N or against the interposed hat-brim; but when the presser-foot is being raised a cam-shaped arm, m³, projecting from the shaft m', comes in contact with the stationary cam-surface d', mounted on the head D', and consequently the shaft m' is caused to turn to the right against the force of the spring m², thus turning the guide M into the horizontal position illustrated in Figs. 3 and 4, and holding it therein while the presser-foot remains raised.

In many cases it is desired to sew between the hat-body and the sweat-leather what is called the "oil-muslin." This is a ribbon of oil-silk or other suitable fabric, having a hem, in which is introduced a thin reed of cane, whalebone, or the like. It is desirable to effect the hemming of the oil-silk and the introduction therein of the reed and the sewing of this member and of the sweat-leather onto the hat all in one operation and by one single line of stitching. For this purpose a gage, O, is used, as illustrated in Figs. 7, 8, and 9. The hem in the oil-silk is formed by the gage o, and the reed is introduced therein through the gage o'. The position of this gage O when in place for use is necessarily such that it would

interfere with the introduction and removal of the hats, and I have therefore devised means for removing the same out of the way with great facility and without necessitating the use of a screw-driver or other tool. The gage O is mounted on the lower extremity of an arm, O', so that it may be adjusted toward and from the needle, as circumstances may require. The upper end of the arm O' is capable of turning with sufficient friction on a screw-stud, d², set in the head D', as represented. Whenever it is desired to introduce a hat into the machine or to remove it therefrom, or to sew sweat-bands onto hats without the intermediate oil-silk, the arm O' is simply turned upward toward the left, thus bringing the gage O out of the way and into a position where it will not interfere with any other part of the machine nor inconvenience the operator in any manner.

Fig. 10 shows a modification of this last feature. According to this construction the presser-foot K is formed with two projecting pins, k², and the gage O with two corresponding closely-fitting holes, as illustrated in dotted lines. When it is desired to use the gage O, it is simply slipped upon the pins k².

Modifications may be made in the details without departing from the principle of the invention or sacrificing the advantages thereof. Certain parts may be used without the others; but I prefer the whole combined and arranged substantially as shown.

I claim as my invention—

1. A sewing-machine for hats and analogous goods, having a goose-neck, D, on one side, and an operating-shaft, B, on the opposite side of the stitch-forming mechanism, in combination with each other and with the lever G, mounted at a lower level, and with the connections F and H, so as to provide clear spaces for the body and brim of the hat, substantially as herein specified.

2. In a machine for sewing sweat-bands onto hats, the guide M, carried on the presser-foot, in combination with means m² m³, connected to the presser-foot, and with a stationary cam, d', whereby the guide M receives a turning motion, in addition to the up-and-down motion, when the presser-foot is raised or lowered, substantially as and for the purposes herein specified.

In testimony whereof I have hereinunto set my hand, at New York city, this 12th day of August, 1882, in the presence of two subscribing witnesses.

VALENTINE MOESLEIN.
